DESIGN FOR A COMBINED SAW AND RULE

Vincent R. Pileggi, Philadelphia, Pa.

Application June 1, 1945, Serial No. 119,838

Term of patent 14 years

(Cl. D93—3)

To all whom it may concern:

Be it known that I, Vincent R. Pileggi, a citizen of the United States, residing at Philadelphia, in the county of Philadelphia and State of Pennsylvania, have invented a certain new, original, and ornamental Design for a Combined Saw and Rule, of which the following is a specification, reference being had to the accompanying drawing forming part thereof.

In the drawing:

Fig. 1 is a side view of a combined saw and rule showing my new design.

Fig. 2 is an enlarged fragmentary view of the saw blade.

I claim as my invention:

The ornamental design for a combined saw and rule, substantially as shown.

VINCENT R. PILEGGI.
